COLLAPSIBLE BUNKHOUSE

Elmer D. Hedrick, Fort Lauderdale, Fla.

Application March 16, 1942, Serial No. 434,969

3 Claims. (Cl. 20—2)

This invention relates to a collapsible and readily portable bunk-house. Its primary object is to provide a shelter which may be erected or dismantled within a very few minutes; when dismantled may be packed into a bundle of very small size in comparison with the capacity of the building; wherein the bunks will be inbuilt and foldable to positions where they will not interfere with the snug packing of the whole structure; wherein improved types of joints between the several sections of the building co-act in such manner as to not only aid in bringing about a very strong and rigid assembly of the whole structure but also provide joints that are absolutely weather-tight even in driving rains; wherein the whole assembly is of very light weight in proportion to the housing capacity that it provides; wherein the building is sufficiently strong and rigid and of such shape as to stand up against even very high winds; wherein the several parts of the building are held in place by novel types of fastening devices, spring retractable to protected positions so that they will not be bent out of shape by accidental blows during shipment.

Further advantages of the invention will be set forth in the detailed description which follows:

In the accompanying drawings, wherein like reference characters designate corresponding parts throughout the several views.

Fig. 1 is a horizontal, sectional view of a building constructed in accordance with the invention.

Fig. 2 is a vertical, sectional view illustrating the inner face of one of the side walls in elevation and with the end walls removed.

Fig. 3 is an end elevation of a building.

Fig. 4 is an enlarged sectional view illustrating the joint between the base and one of the side walls;

Fig. 5 is an enlarged horizontal sectional view upon line 5—5 of Fig. 3, illustrating the joint at one of the vertical corners of the building.

Fig. 6 is an enlarged sectional view of the joint between the roof section and one of the side or end walls.

Fig. 7 is a sectional view like Fig. 5 but taken in a plane other than that at which the bolt is located.

Fig. 8 is a fragmentary vertical sectional view through one of the side walls.

The building of the present invention comprises a base 5, a roof 6, a pair of end walls 7 and a pair of side walls 8. The end walls (only one of which is shown) are preferably of identical construction and a description of one will serve as a description of both. The base comprises a floor 9 that is supported upon and firmly secured to sills or stringers 10. This floor is preferably made

of waterproof plywood. A support for the side walls is provided by rails 11, said rails being secured by bolts 12 to the stringers 10. The side walls are made up of the stiles or rails 13 arranged to form a rectangular frame and having its open sides closed by relatively light weight but waterproof composition or plyboard, indicated at 14. The end walls are of substantially the same construction comprising the stiles 23 and the plyboard 16. However, these end walls are provided with doorways 11 for the reception of doors 18. They are also provided with louvers 18a. The nature of the joints between both the side and end walls and the floor is illustrated in Fig. 4 and by referring to that figure it will be seen that the upper faces of the rails 11 are provided with up-standing V-shaped ribs 19 which enter corresponding recesses 20 formed in the bottom of the side and end walls. Bolts 21 having any suitable drawing means associated therewith, such as the thumb-nuts 22, pass through the stiles 19 and have their lower ends so shaped as to engage any suitable form of fixed element 19a carried by the rails 11. These fixed elements may be the bolt 12 or a simple pin as desired. It will be apparent that when the thumb-nuts are tightened the stiles 13 will be drawn forcibly toward the rails 11 and that in this drawing action the ribs 19 and grooves 20 will function to not only lock the stiles against lateral movement outwardly with respect to the rails 11, but they function to guide and thrust these stiles forcibly toward those portions of the stringers or sills 10 which project above the rails 11. Further, the up-standing ribs 19 break the otherwise straight joint between the confronting faces of the stiles and rails 11 and effectively prevent the passage of wind or water therethrough.

The joints at the corners of the building are illustrated in Figs. 5 and 7. The vertical stiles 23 of the end walls meeting the vertical stiles 24 of the side walls with their confronting faces disposed at an angle of approximately 45° as indicated at 25 but having the length of the joint interrupted by a V-shaped rib 26 upon one of said parts which takes into a V-shaped groove 27 upon the other of said parts. Bolts 28 slidably disposed in one of said parts are provided with hook-shaped ends 29 adapted to engage over fixed elements, such as pins 30, carried by the other of said parts. The material of the ribs 26 is notched at points in alignment with said hooks to provide recesses 31 into which said hooks may pass in the act of engaging them with the pins 30. If the pin and recess is carried by the part 24, then the part 23 will be provided with recesses 32 into which the hooks 29 may be drawn under the influence of springs 33 when the building is collapsed and the parts are being shipped from place to place. The purpose of withdrawing these hooks is to pro-

tect them against accidental bending. When the time of use arrives the bolts are thrust inwardly against the tension of the springs 33 until the hooks 29 can be engaged over the pins 30. During this action the hooks may be turned sideways while passing over the pins. Subsequent tightening of the thumb-nuts 34 results in drawing the corners into tight engagement with each other, in properly lining up the parts and in forming a weather-tight joint. This formation of a weather-tight joint is facilitated by the presence of the ribs and grooves which break the line of what would otherwise be a straight joint.

The type of joint employed between the rails 11 and stiles 13 is also employed between the top stiles or plates of the side walls 35 and rails 36. These rails 36 constitute the frame work of the roof. The roof proper preferably consists of light weight weather-proof board which may be ply-board, hard-board or any other of the composition materials now so widely used. Joists 37 spaced at intervals along the roof have their upper surfaces shaped to form a relatively flat arc. The curvature of the roof is sufficient to shed water but the relatively flat arc results in providing a roofing element adapted to be packed along with the side walls, end walls and floor into a shipping bundle of very little height. The side walls are stiffened by vertical studs 38 and horizontal stringers 39. Bunks consisting of simple endless tubing 40 having canvas webbing laced thereto, as indicated at 42, are pivotally mounted in suitable fixtures 43 so that they may occupy the horizontal positions illustrated in Fig. 1 or they may be swung up to the vertical positions illustrated in Fig. 2. When in lowered position these bunks are supported by pivoted folding links 44 and when in vertical position they lie within the recesses provided by the studs, rails 39 and stiles of the side walls. In addition, the lower bunks may be provided with stiffening legs 44^a comprising short sections of pipe engaged with T's that are pivotally mounted upon the frame tubing of the lower bunks. These bunks are so thin that no part of them projects beyond the faces of the studs and thus the side walls and bunks may be packed as a unit for shipment and occupy very little space. As a matter of fact, the capability of close packing inherent in this structure is such that a full-size eight man bunkhouse when packed for shipment constitutes a package only 20 inches in height. The joists may carry slats 45, constituting racks in which articles may be placed. The louvers 18^a are of conventional form and need no particular description. These louvers may be screened and provided with waterproof curtains on the inside of the building if desired. However, these are not features of invention and are not shown. The doors 18 may be of any suitable type, though they are preferably so made as to provide glass carrying panels 46 and louvers 47. The glass carrying panels 46 are mounted to slide in ways 48 so that they may be raised into the position illustrated in Fig. 3 or they may be lowered in said ways into a position where they will overlie the louvers and uncover the opening 49, which they close when in their upper position. A waterproof curtain 50 is disposed to cover the outside of the louver in inclement weather and an insect screen 51 is disposed on the inside of the louver. An insect screen 52 may be placed over the opening 49.

From the foregoing it will be seen that the proposed construction is of light weight, may be cheaply manufactured, requires but little metal, may be erected or collapsed in a few minutes, may be packed into a bundle of small size for shipment with all of the parts including the bunks in place so that they will be ready for instant use when the building is being erected, wherein the building is made very rigid to resist any accidental collapse under wind pressure or otherwise and wherein the joints are of such a nature that the tightening of the fastening exerts both a vertical and a lateral drawing action to bring about suitable binding of the parts against each other, the resultant joint being weather-tight under even severe driving rains and high winds. In addition, I cause the joists to serve as a support for inbuilt lighting fixtures. An electric bulb is indicated at 53 in Fig. 8, this bulb being located at the end of a section of conduit indicated at 54. This conduit has upon its outer end and outside of the roof, a plug-in socket 55. There may be two or more of these lighting fixtures and they provide means whereby a source of lighting supply may be plugged into the socket 55 and the building lighted inside of a minute after its erection.

It is to be understood that the invention is not limited to the precise construction set forth but that it includes within its purview whatever changes fairly come within either the terms or the spirit of the appended claims.

Having described my invention, what I claim is:

1. In a collapsible building the combination with sills arranged to constitute a rectangular frame, a floor supported thereon, rails secured to and extending along the outer sides of the sills and having their upper faces disposed a material distance below the tops of the sills, the upper faces of said rails carrying upstanding ribs extending lengthwise thereof and of tapering formation in cross section, vertical walls supported upon said rails and comprising bottom stiles having their under faces provided with grooves shaped to receive said ribs, the location of said ribs and grooves, and their shapes, being such as to guide and hold the inner sides of the said lower stiles into close contact with the outer sides of those portions of the sills which lie above the sill carried rails.
2. A structure as recited in claim 1 in combination with horizontal bolts traversing the sills and rails for binding them together, vertical bolts passing through the bottom stiles of the side walls and having lower ends engaged with fixed members of the rails and drawing means upon the vertical bolts for drawing the side walls forcibly down upon the said ribs.
3. A structure as recited in claim 1 in combination with horizontal bolts traversing the sills and rails for binding them together, vertical bolts passing through the bottom stiles of the side walls and having lower ends engaged with fixed elements of the sills and thumb nuts threaded upon the vertical bolts and acting against the upper faces of said bottom stiles to thrust the side walls forcibly downward upon the ribs to cause said ribs by their tapering formation to thrust the side walls into weather-tight engagement with the outer sides of the sills.

ELMER D. HEDRICK.
